(57) **CLAIM**

The ornamental design for the scissors, as shown and described.

DESCRIPTION

FIG. 1 is a top plan view of scissors showing our new design;

FIG. 2 is a front view of the scissors of FIG. 1;

FIG. 3 is a bottom plan view of the scissors of FIG. 1;

FIG. 4 is a rear view of the scissors of FIG. 1;

FIG. 5 is a left side view of the scissors of FIG. 1;

FIG. 6 is a right side view of the scissors of FIG. 1; and,

FIG. 7 is a top plan view of the scissors of FIG. 1, rotated approximately 90° and illustrated in an open position.

The broken lines shown in the figures are for illustrative purposes only and form no part of the claimed design.
